UNITED STATES PATENT OFFICE

116,307

DESIGN FOR A TRACTOR

Verne F. Hobbs, Milwaukee, Wis., assignor to Alis-Chalmers Manufacturing Company, Milwaukee, Wis., a corporation of Delaware

Application January 30, 1939, Serial No. 82,679

Term of patent 14 years

To all whom it may concern:

Be it known that Verne F. Hobbs, a citizen of the United States, residing at Milwaukee, in the county of Milwaukee and State of Wisconsin, has invented a certain new, original, and ornamental Design for Tractors, of which the following is a specification, reference being had to the accompanying drawings, forming part thereof.

Fig. 1 is a perspective side view of a tractor, showing the new design.

Fig. 2 is a perspective three-quarter rear view of the tractor shown in Fig. 1, also showing the new design.

I claim:

The ornamental design for a tractor, as shown.
VERNE F. HOBBS.
